Osgar L. Hommedieu 1114X
Sellers Patent.

The Schedule referred to in the Sellers Patent and making part of the same containing a description in the words of the said Osgar L. Hommedieu himself of his double pointed contrivance Auger.

This auger at the end of which only the timber has a screw in the centre which supersedes the necessity of a gouge. The auger as its name imports is made with two tools, directly opposite to each other, and at the extremities of which near the surface are two sharp lips for cutting the timber. The auger may be made of any dimensions. The shaft and handle like those in common use otherwise at the pleasure of the owner. The great superiority of this auger over every other in use consists in its being more strong and durable, in turning much easier, being faster and drawing out of the hole with more ease.
